CLAIM

The ornamental design for a decorative frame, as shown and described.

DESCRIPTION

FIG. 1 is a side perspective view of a frame for a decorative frame showing my new design.

FIG. 2 is a front elevational view;

FIG. 3 is a top plan view;

FIG. 4 is a side elevational view;

FIG. 5 is a rear elevational view; and,

FIG. 6 is a bottom plan view.

The broken lines are for illustrative purposes only and form no part of the claimed design.
